UNITED STATES PATENT OFFICE.

LOUIS N. LA FAYETTE, OF PLYMOUTH, MASSACHUSETTS.

SMASH PROTECTOR.

Application filed April 26, 1923. Serial No. 634,812.

My improvement relates to a mechanical smash protector for use in a fancy loom which, when two shuttles are in opposite shuttle boxes at the two ends of the shuttle race and the lay is in its beating-up position, will operate the stop motion before the next throw of the shuttles begins. Thus the stop motion operates before either shuttle starts to leave its box and no smash will 10 take place.

My invention will be understood by reference to the drawings in which it is shown in its preferred form. As the mechanism for operating the lay, and the stop motion may 15 be of any suitable kind they are not shown.

Figure 1 is a cross section of the lay and breast beam in beating-up position, my improved mechanism being shown in side elevation and in normal position, the shuttle 20 box shown being empty.

Fig. 2 is a similar view showing the position of my mechanism when shuttles are in opposite boxes and the parts are set to operate the stop motion when the lay starts 25 backward.

Fig. 3 is a similar view in which the lay has moved backward a short distance (not sufficiently far to operate the picker staffs); and the lay is locked to the breast beam and 30 the stop motion has been operated.

Fig. 4 is a plan of the parts when in the position shown in Fig. 3.

Fig. 5 is an elevation of the parts attached to the lay in normal position, and 35

Fig. 6 is an elevation of the parts attached to the breast beam in normal position.

In the operation of my mechanism, when there are shuttles in two opposite boxes, as the lay approaches the breast beam it sets 40 the mechanism so that as the lay begins to move backward, parts on the lay and breast beam engage momentarily and operate the stop motion and at the same time the lay is locked in approximately its forward position from which it is again released by the releasing of the stop motion.

In the drawings, 1 is the breast beam and 2 is the lay carrying on its top the shuttle race as usual. 3 are the shuttle boxes and 4 50 are the shuttle binders, α being a shuttle. 5 are fingers each mounted fixedly on one of the two shafts 6, 61, which shafts are in line.

Each shaft has a spring 7 wound round it and connected thereto, each spring being arranged so that its shaft will hold its finger 55 against the binder 4.

These shafts are supported in bearings 9 and 10. The bearings 9 are supported on the lay sword 11 and the bearings 10 are supported on a plate 12 which is attached to the lay. Collars 13 are attached to the shafts 6 and 61 to hold them in proper position in the bearings. The shafts 6, 61 carry arms 8 at their opposing ends, which are attached at their outer ends by links 14 to holders 15, which holders are pivoted to the bracket 16 mounted on the lay. 17 is an arm shown in the form of a loop which has projecting from it a rod 18 mounted in an arm 181 on a stud 19, which is supported in bearings 20 70 hung below the lay beam 2.

It will be seen by reference to Fig. 1 that when the shuttle boxes are empty so that the binders are in their normal position, the fingers 5 being in the position shown in Fig. 75 1, the holders 15 will support the rod 18 and when both holders drop into the position shown in Fig. 2 the rod 18 drops carrying with it the loop 17, and this only takes place when there is a shuttle in each box, the loop 80 being thus brought into position to engage cooperating parts on the breast beam which cause the operation of the stop motion.

The stop motion may be of any convenient construction and is attached to the shaft 21 85 mounted between the supports 22 of the breast beam 1 in the usual way, and the stop motion is operated by means of an arm 23 attached to the shaft 21 so that when the arm 23 is depressed it will turn the shaft 21 90 slightly, but sufficiently to operate the stop motion. The arm 23 is depressed by means of a stud 24 which is mounted on a hook lever 25 carried by a stud 26 on a bracket 27 attached to the breast beam 1, this construction being such that the depression of the hook lever 25 will cause also the depression of the arm 23.

The hook lever 25 is depressed by engagement with the loop piece 17. The rod 18 is 100 normally supported by the holders 15. When a shuttle enters its box and operates the finger by moving the binder 4 outwardly it depresses its holder 15, but the other

holder not being depressed the loop still remains in its inoperative position. When, however, fingers in opposite shuttle boxes are moved outwardly because of shuttles in 5 opposite boxes, both holders 15 drop and release the loop 17 so that it drops into position to engage the hook lever 25 as the lay completes its beating-up stroke and depresses it as the lay starts back.

10 The hook lever 25 has pivoted to its stud 24 a link 27' which is attached to a lock lever 28 pivoted at 29 to the bracket 30. This lock lever and its functions are shown particularly in Figs. 4 and 6. 31 is a slide 15 the position of which is controlled by a spring 32 attached to the T-lever 33 pivoted to the bracket 34, this lever 33 carrying a cam arm 35.

In Fig. 6 the parts are shown in their 20 normal position when the loom is running. 36 is a plate attached to the breast beam 1 and having in it a recess 37. The plate 36 also has in it ways in which the slide 31 runs and when the loom is running under 25 ordinary conditions the parts are as shown in Fig. 6. The slide 31 has also an opening slightly narrower than the opening 37, these openings normally registering as shown in Fig. 6. Normally the lock lever 28 engages a notch 38 in the slide 31 as indicated in Figs. 1 and 2. The drag of the loop 18 over the toe of the hook lever 25 depresses the outer end of the hook lever and pulls the lower end of the lock lever 28 by means 30 of the link 27' against the force of the spring 39 and disengages it from the slide so that the slide is thrown to the left (see Fig. 6) by the spring 32 acting through the T-lever 33 and takes the position shown in 40 Fig. 4 to engage the hook 40 (see Fig. 4). This hook is made fast to the lay beam by bolts 41 so that it is immovable except as it is moved with the lay and is located on the lay beam so that it will reciprocate 45 through the opening 37 and the corresponding opening in the slide 31. When, however, the hook lever 25 is depressed by engaging with the loop 17, sufficient movement is given to the lock lever to disengage 50 it from the slide 31 so that the slide is pulled back by the spring 32 into engagement with the hook 40, thus holding the lay from further rearward movement (see Fig. 4).

To the shaft 21 is attached also the arm 55 42 and to the T-lever 33 is attached a cam arm 35 in position to be struck by the arm 42 when the machine is reset and so return the slide to its normal position. It may also assist in operating the stop motion by 60 engaging the arm 42 when the lock lever 28 releases the slide 31 and the spring 32 acts to turn the T-lever 33 and so moves the cam lever 35.

To release or reset the stop motion so that 65 the machine will again start up, a handle 44

is mounted on shaft 21, which being moved slightly to turn the shaft 21, resets the stop motion in the usual way and also causes the engagement of the arm 42 with the cam arm 35 (see Fig. 6) so that the T-lever will reset the slide 31 in the position shown in Fig. 6 and Fig. 3. The lever 28 is again thrown into the notch 38 by the spring 39 to hold the slide out of engagement with the hook 40 as the lay moves under normal conditions. The end of the arm 23 lifts the stud 24 and hook lever 25 into normal position. The normal position of the hook lever 25 is controlled by the spring 39 acting through the link 27' so that, except when the loop 17 engages it, it normally stands in substantially the position shown in Figs. 2 and 3 yielding somewhat as the loop 17 when in its lower position passes over it.

From the above it will be seen that when 85 one shuttle x is in the shuttle box one only of the holders will be dropped, but when shuttles are in opposite shuttle boxes both holders will be dropped so that the loop 17 drops over the hook lever 25 as shown in Fig. 2 and engages the toe of the hook lever 25 as the lay starts back, thus pulling the lock lever 28 out from the notch 38 and allowing the slide to move under the influence of the spring 32 acting 90 through the T-lever to which the slide is pivoted, this movement taking place after the hook 40 has moved through the opening 37. The hook and lay are thus locked 95 to the breast beam.

It will be evident to those skilled in the art that my invention may be otherwise embodied. It is shown in a form which is simple to construct and has proved very efficient in practical use, and being entirely 105 mechanical is more certain of operation than if electrical and dependent for its successful operation upon electric contacts which are hard to keep clean in a mill.

What I claim as my invention is:—

1. A mechanism of the kind described comprising a lay having a shuttle race and a shuttle box at each end thereof, a beam having a stop-motion-operating mechanism located thereon and comprising a shaft having an arm mounted thereon to turn said shaft, and means for moving said arm comprising a lever mounted on said beam, and mechanism located on said lay and normally 110 out of register with said lever, means connected with each shuttle box adapted to be operated by a shuttle in said box, whereby when both shuttle boxes contain a shuttle said last-named mechanism will be brought into register with and will engage said lever 115 on the beating-up motion of the lay to cause said lever to move said arm and operate said stop motion to stop the loom and latching means comprising two members one attached to said lay and the other to said beam and 120 125 130 135 140 145 150 155 160 165 170 175 180

connections between said stop motion operating mechanism and one of said members whereby it will be operated when engaging the other member and stop the lay when said stop motion is operated.

2. A smash protector comprising a breast beam, a lay carrying a shuttle box at each end thereof, each shuttle box containing a binder, two holding levers, means connected to each binder for holding them normally in holding position and allowing them to move out of holding position when a shuttle engages the corresponding binder, a rod mounted to lie parallel to the lay and normally resting on said holders and carrying an arm, whereby when both holders are moved out of holding position said rod and said arm will drop, in combination with a stop motion mechanism located on said breast beam and comprising an arm and means adapted to move said arm to stop said loom when said first-named arm is in dropped position and means for positively locking said lay and said breast beam operable by said stop motion operating mechanism.

3. A smash protector comprising a lay carrying a shuttle box at each end thereof, and a breast beam carrying a shaft adapted to operate a stop motion and means for turning the shaft to stop the loom comprising an arm mounted on said shaft, and means adapted to move said arm comprising a hook lever having means thereon to engage said arm, and means located on said lay adapted to be operated when opposite shuttle boxes contain shuttles to engage and operate said hook lever to cause it to move said arm when the lay is on its beating-up stroke and means for locking said lay upon the opera-

tion of said stop motion connected to said hook lever and adapted to be operated thereby to lock said lay and said breast beam.

4. In a machine of the kind described, a lay having a shuttle box at each end, a breast beam, a hook attached to said lay and adapted to be moved towards said breast beam, and a slide mounted on said breast beam and adapted to move on said breast beam to engage and hold said hook, a lock lever adapted to lock said slide out of possible engagement with said hook, a spring adapted to pull said slide into engagement with said hook when said lock lever is released, and means operable by the entry of shuttles into two opposite shuttle boxes and the beating-up stroke of the lay whereby said hook will be placed in position to be engaged by the slide and the lock lever will be caused to release the slide and the slide will engage the hook.

5. In a smash protector, a lay and a breast beam, a hook connected to said lay and a slide mounted on said breast beam and adapted to engage and hold said hook, and means for operating said slide comprising a lever mounted on said breast beam and connected to said slide, a spring one end of which is connected to said breast beam and the other end to said lever, a latch adapted to engage said slide and hold it against the force of said spring, means attached to said lay adapted to release said latch, a shaft adapted to operate a stop motion and carrying an arm, and means attached to said lever and adapted to be engaged by said arm, whereby said lever and said slide will be moved and said slide will be locked by said latch.

LOUIS N. LA FAYETTE.
